Inventor:

Francis M. Aday,

By his Attorney,

McClure & Carton.

UNITED STATES PATENT OFFICE.

FRANCIS M. ADAY, OF BROOKLYN, NEW YORK.

VACUUM LIFTING DEVICE.

Application filed June 3, 1925. Serial No. 34,584.

To all whom it may concern:

Be it known that I, FRANCIS M. ADAY, a citizen of the United States, and a resident of Brooklyn, in the county of Kings and 5 State of New York, have invented new and useful Improvements in Vacuum Lifting Devices, of which the following is a specification.

The invention relates to improvements in 10 the method of lifting, conveying, handling and discharging cakes or blocks of ice and more particularly to the lifting or hoisting of cakes of ice directly from stationary cans or molds in which the water has been frozen. 15 The main object of the invention is to provide improvements in such lifting, conveying, handling and discharging of cakes of ice whereby the present method of freezing rods or pipes into the ice may be eliminated 20 with the resultant necessity of removing same at the discharging point and the undesirable cavities or holes which result from such removal.

A further object of the invention is to 25 provide improvements whereby the necessity for lifting the can from the tank and discharging the ice by tilting same in a suitable cradle or ice dump may be avoided.

The specific object of my invention is to 30 provide a simple, durable and effective, yet relatively inexpensive, device especially adapted for the lifting, conveying, handling and discharging of ice blocks, the same being set forth in detail in the following 35 description and drawings forming a part thereof, in which;

Figure 1 is a perspective view showing an ice hoisting apparatus embodying my invention.

Figure 2 is a longitudinal section of a 40 downwardly opening chamber made of sheet steel or other heat conducting metal or material which may be rectangular in shape but will have preferably sloping sides as illustrated in;

Figure 3 which is a transverse section on the line 3—3 of Figure 2 and which is further illustrated in

Figure 4 which shows my invention perspective.

Referring to the drawings, the reference numeral 1 designates the top or upper surface of this downwardly opening chamber, 2 the ends thereof, 3 the sloping lateral sides and 4 the sloping lateral top walls.

A suitable heating coil, preferably of the

type commonly employed in electrical heaters or irons wherein a high resistance coil is imbedded in or caused to envelop a refractory insulating material as porcelain, 60 soap stone, or the like, is mounted either substantially entirely around or partially around the periphery of the said receptacle or chamber.

The object of this heating coil as will be 65 later described, is to provide a means for warming the metal of which the chamber is made and especially to provide a heating effect to the lower edges of the downwardly opening chamber.

A flexible or resilient flap 6 may be secured to the end and lateral walls of the chamber adjacent the lower margin thereof in order to provide a seal between the lifting chamber and any block of ice with which 70 it may come in contact, although ordinarily it can be dispensed with.

A ring 7 for engaging a lifting hook or other suitable lifting means is tightly secured to the top of said chamber or receptacle and an air exhausting valve 8 and vacuum relief valve 9 are provided for respectively permitting the production of a vacuum in the receptacle and the relief of same with the re-establishment of atmospheric pressure 75 in such receptacle when desired.

Having described the construction of this device I now describe the manner in which it is to be used, especially for lifting blocks of ice from molds in which the ice has 80 been formed.

First, electric current is supplied to the heating coils and the heat produced is conducted by the metal sides of the vacuum receptacle or chamber to all parts of same. 85 When the chamber is lowered into contact with the top of an ice block if the upper surface of the ice should be uneven the edges of the chamber will slowly melt that part of the ice beneath the edges due to the warmth of the metal. When this melting has proceeded for a short period the edges of the chamber will have sunk into the ice at all points sufficiently to provide and insure a

perfect contact between the ice and the edges 100 of the chamber which will compensate for any unevenness in the surfaces of the ice or in the edges of the chamber. At this point the air exhausting valve 8 is opened to connect the chamber with a vacuum pump or other air exhausting means, thus creating in the chamber a pressure less than the at- 105

mospheric pressure outside of same. The total difference of pressure measured over the projected surface of the edges of the chamber will produce a large total force tending to press the chamber tightly in contact with the ice block, and when by reason of the increasing vacuum this total pressure exceeds the weight of the ice block there will be sufficient adhesion between the chamber and the block so that by lifting on the hook of the chamber the block of ice can be raised.

After the block has been lifted by the hoisting mechanism of the crane or other lifting means the crane can be moved to any point where it is desired to discharge or release the ice. At this point the vacuum relief valve 9 is opened and the air rushing into the chamber from the atmosphere will relieve the vacuum and re-establish equal pressures inside and outside of the chamber. When the difference in pressure between the outside and the inside becomes less than the weight of the block of ice the block will be released.

Having described the construction and operation of this vacuum chamber I now describe the manner in which a multiplicity or battery of these chambers can be conveniently arranged to lift more than one block of ice or a whole row of blocks of ice.

Referring to Figure 1. A number of these receptacles 1, as already described, are arranged to be suspended by means of their lifting hooks from the cross beam 12 by short rigid rods 11. This cross beam 12 in turn is supported by cables 13 passing over sheaves 14 and 14' which are arranged to be wound upon the drum 15 operated through meshing gears 16 and 17 by a motor 18. By the turning of the drum the cross beam 12 and receptacles 1 can be raised or lowered for lifting or lowering the blocks of ice. This hoisting drum is mounted upon the cross members 19 of a travelling crane which is free to travel back and forth on the rails 20.

Also mounted upon the cross beam of this crane is a tank or receiver 21, wherein a vacuum can be produced, connected by suitable pipes to an air exhausting pump or other vacuum producing means 22 operated by a motor 23. The receiver 21 is also connected by a pipe 24 to a flexible hose connected with another pipe 24' on the cross beam 12 and thence to each of the vacuum receptacles by flexible hose 25.

Now when the crane is brought over a row of blocks of ice and the chambers lowered into contact therewith, by the operation of the three-way cock 26 a vacuum can be produced in all of the chambers at one time and the ice can be lifted from the molds by the hoisting mechanism of the crane. After the crane has moved the ice to the desired point

the vacuum can be relieved beneath all of the chambers by means of the said three-way cock 26 which shuts off the vacuum and admits the atmospheric air into the chambers thus releasing the ice blocks from the chambers.

Not only has the above described vacuum chamber the advantage of not requiring rods to be frozen into the ice or the tilting of cans in order to remove the ice but this device also renders it possible to readily hoist and transport large cakes of ice with the minimum of effort on the part of the operator and the ice is not materially disfigured by the application of these vacuum receptacles thereto since the extent to which the lower edge sinks into a cake of ice is relatively small.

It has the further advantage that a few of these vacuum chambers will replace many of the rods or pipes which are ordinarily frozen into the ice since one of them must be employed for each mold or can in an ice making plant.

This device moreover has the further advantage that it can be operated singly for one block of ice or that batteries of them can be provided for handling a number of blocks at one time and likewise the valves for controlling the production of vacuum and also for relieving same can be applied to each chamber individually or the single three-way cock 26 can be employed to control all of the chambers simultaneously.

While I prefer to employ means for heating the walls of the receptacles which are preferably of metal or heat conducting material, nevertheless this device will operate most satisfactorily on smooth level surfaces of ice without applying any heat or even without providing means for heating the same as the ordinary heat contained in the metal will be sufficient to produce some melting effect with such blocks of ice and also since the weight of the chamber will be sufficient to provide some melting effect beneath the thin edge of the chamber upon which its weight rests. Certainly, however, it is found extremely desirable to provide means for heating the walls of the receptacle to permit of the partial penetration of the lower edge *d* thereof into the upper surface of the ice cake and this feature alone is of extreme importance when it comes to operating on uneven surfaces of ordinary cakes of ice it is commonly necessary to lift and transport especially if the same has formed an uneven surface during freezing and has become roughened or rendered uneven by the shipping of same in handling these relatively large objects.

While I have shown a heating coil preferably extending substantially around the entire periphery of the receptacle or chamber it is obvious that either several short sec-

tions of the heating coils may be secured to the receptacle or merely a single short section may be secured to the top of the receptacle as the conductivity of the metal 5 from which the same are made will serve to transmit the heat to the surface of the ice brought into contact therewith and thereby facilitate the sinking of the lower edges *d* of the receptacle into the surface of the 10 ice cakes until a perfect seat or line of contact is obtained between the lower edges of the receptacle and the ice beneath these edges.

As an illustration of the effect of the lifting power of my improved device, the following example is given:

A receptacle, say 10" x 20", which would have an area of 200 square inches, when placed on a block of ice and in which a 20 vacuum of 10" is produced said 10" of vacuum equalling about 5 lbs. pressure, will exert a pull equivalent to approximately 5 lbs. per square inch or 1000 lbs.

The manner of suspending the vacuum receptacles from the cross beam 12 by rigid rods 11 which by means of the hook and eye connections are capable of tilting slightly either transversely or longitudinally but are held against rotation on a vertical axis, makes 25 it possible to automatically, without manual adjustment of each receptacle, drop such receptacles when properly spaced from each other on a series of blocks of ice while still in their respective cans while at the same 30 time the receptacles will be aided in seating themselves by the weight of the cross beam to which they are attached.

Although I have described my improvement in great detail and with respect to a 40 preferred form thereof I do not desire to be limited to such details or form since many changes and modifications may be made and the invention embodied in a widely 45 different form without departing from the spirit and scope thereof in its broader aspects. Hence I desire to cover all modifications and forms coming within the language and scope of any one or more of the appended claims.

Having thus described my invention, what I claim and desire to obtain by United States Letters Patent is:

1. In an ice hoisting device, the combination comprising a vacuum receptacle, means affording communication with a vacuum producing means, means for connecting a hoisting device to such receptacle and means

for heating the walls of such receptacle in order to melt portions of the ice surface immediately adjacent such heating means and thereby afford an air-tight contact between the vacuum receptacle and the ice surface. 60

2. In an ice hoisting device, the combination comprising a vacuum receptacle, means affording communication with a vacuum producing means, means for connecting a hoisting device to such receptacle, separate means for admitting atmospheric air to such receptacle and means for heating the walls of such receptacle in order to melt portions 70 of the ice surface immediately adjacent such heating means and thereby afford an air-tight contact between the vacuum receptacle and the ice surface.

3. In a vacuum device for hoisting ice, 75 the combination comprising a receptacle, certain of the lateral walls of the same being sloping, means for heating the walls of said receptacle in order to melt portions of the ice surface immediately adjacent such heating means and thereby afford an air-tight contact between the vacuum receptacle and the ice surface, valve control means connected to such receptacle and adapted to afford communication between the interior 80 of such receptacle and a vacuum producing means and means secured to said receptacle for connecting the same to a hoisting device. 85

4. A vacuum device for hoisting ice, comprising a receptacle open at its lower end and adapted, when the edges of its lateral walls are in intimate contact with a cake of ice, to form a sufficiently tight seal to permit of the partial evacuation of such receptacle, means for heating the walls of said 90 receptacle in order to melt portions of the ice surface immediately adjacent such heating means and thereby afford an air-tight contact between the vacuum receptacle and the ice surface. 95

5. A vacuum device for hoisting ice, comprising a receptacle having one open end only, means for heating the walls of said receptacle in order to melt portions of the ice surface immediately adjacent such heating means and thereby afford an air-tight contact between the vacuum receptacle and the ice surface and valve control means permitting of connecting the interior of said receptacle with vacuum producing means. 105

Signed at New York, in the county and State of New York this 2nd day of June 1925.

FRANCIS M. ADAY.
